UNITED STATES PATENT OFFICE.

EUGENE LEE BUTTON, OF BROOKLYN, NEW YORK.

DESIGN FOR A BOX.

SPECIFICATION forming part of Design No. 21,796, dated August 23, 1892.

Application filed June 22, 1892. Serial No. 437,655. Term of patent 7 years.

To all whom it may concern:

Be it known that I, EUGENE LEE BUTTON, a citizen of the United States, residing at Brooklyn, in the county of Kings and State of New York, have invented and produced a new and original Design for a Box; and I do hereby declare the following to be a full, clear, and exact description of the same, reference being had to the accompanying drawing, forming a part thereof.

The leading feature of my design is the entire configuration of the box; and it consists in the contour shown in the drawing, the lower part A being cylindrical in form, having the base of a diameter slightly in excess of the diameter of the main portion of the receptacle formed by the flat-faced beads 1 and 2, the base-beads having unequal diameters, the diameter of the lower base-bead 2 being slightly in excess of the upper bead 1. The central part of my receptacle B has near its lower

portion a bead 3 of diameter about the same as the base-bead 2, which is surmounted by an oval bead 4, presenting a slightly-greater diameter, which in turn is surmounted by the progressively-decreasing oval beads 5, 6, and 7, terminating in the flange 8, the surface between the bead 4 and flange 8 presenting a corrugated appearance by reason of the beads. The top C is bell-shaped, having a flat crown.

Having thus fully described my invention, what I claim as new, and desire to secure by Letters Patent, is—

The design for a box, as herein shown and described.

In testimony whereof I affix my signature in presence of two witnesses.

EUGENE LEE BUTTON.
